UNITED STATES PATENT OFFICE.

CHARLES DRADER AND RAPHAEL ROGERS CANDEE, OF BAKERSFIELD, CALIFORNIA.

NON-LEAK SEAT AND ANCHOR FOR LINER-PUMPS

1,151,765.

Specification of Letters Patent. Patented Aug. 31, 1915.

Application filed December 13, 1913. Serial No. 806,631.

To all whom it may concern:

Be it known that we, CHARLES DRADER, a subject of the King of Great Britain, and RAPHAEL ROGERS CANDEE, a citizen of the 5 United States, both residing at Bakersfield, in the county of Kern and State of California, have invented a new and useful Non-Leak Seat and Anchor for Liner-Pumps, of which the following is a specification.

10 This invention relates to a seat for liner pumps which may serve to anchor a stand valve in the shoe of the ordinary liner pump, and may also serve to anchor the working barrel in the tubing of a removable liner 15 pump.

An object of the invention is to provide a positive non-leak seat which finds particular utility to secure working barrels of removable liner pumps in the tubing.

20 A further object is to eliminate all possibility of an accumulation of sand behind the working barrel walls which would "freeze" and make removal of the working barrel difficult.

25 In the pump working barrel, the stand valve and shoe of the tubing, and in the removable liner pump the working barrel and tubing are attached only temporarily.

A further object of the present invention 30 is to provide an anchor that will quickly and with facility secure together these temporarily anchored parts of the liner pump construction.

It is a still further object of the invention 35 to provide temporary anchoring means whereby the parts temporarily anchored together can very quickly and with facility be disconnected.

Still another object of the invention is to 40 provide a combined non-leak seat and anchor that can be manufactured at low cost and without in any way requiring the reconstruction of liner pumps now in use.

The important features, capabilities and 45 advantages of the invention will become apparent from the subjoined detail description of certain specific embodiments thereof.

The accompanying drawings illustrate the invention.

50 Figure 1 is a side elevation of the upper end of a removable barrel, showing the anchor before being used. Fig. 2 is a side elevation of the shoe of the removable barrel showing the anchor before being used.

55 Fig. 3 is a fragmental section of a removable liner pump having a removable barrel

provided with the present anchor and wedged into the tubing. Fig. 4 is a fragmental section similar to Fig. 3 showing a different form of removable working barrel equipped with the present anchor and wedged into the tubing. Fig. 5 is a section of the lower end of a stationary working barrel showing a stand valve equipped with the present anchor wedged into the shoe of 65 said working barrel. Fig. 6 is an elevation of a stand valve of the construction shown in Fig. 3 detached, showing the anchor before being used.

In the construction shown in Figs. 1, 2 70 and 3 the invention is shown in connection with a removable liner pump. The lower end of the main pump stock or tubing 1 is provided with an external screw thread to receive the upper end of a collar 2 having 75 an intermediate diminished bore 3 and a lower end internally screw-threaded to receive the upper externally screw-threaded end of the section of tubing 4. The lower end of the tubing section 4 is externally 80 screw-threaded to receive the upper end of a shoe 5 which has an inner tapered face 6 at its lower end. Between the collar 2 and the shoe 5 a removable working barrel 7 is secured in the operation of the pump. 85

The working barrel 7 is externally screw-threaded at its upper end to receive the sleeve 8, which has a diameter just sufficient to pass through the diminished bore 3 of the collar 2. The lower end of the working 90 barrel 7 is externally screw-threaded to receive the main valve seat 9 which has a lower tapered portion 10 to fit into the inner tapered face 6 of the shoe 5.

To secure the working barrel in position 95 in the operation of the device the sleeve 8 and main valve seat 9 are equipped with the novel non-leak seat and anchor forming the main part of the present invention. For this purpose the outer face of the sleeve 8 100 is provided with the ductile metal ring 11 made of soft pliable metal, such as lead or the like. To properly anchor the metal ring on the sleeve 8, there is provided in the present instance an annular groove 12 in 105 the face of the sleeve 8 in which the metal ring is lodged. The ductile metal ring 11 projects out from the face of the sleeve 8 sufficiently (see Fig. 1) so that when said sleeve 8 is moved into the collar 2, it will 110 come into contact with the inner face of the collar 2; and the metal of said ring will be

sufficiently soft so that as said sleeve 8 is forced down into the collar 2 it will spread and offer sufficient resistance, so that said sleeve will be adequately anchored in said collar. At the same time the anchor will not be so tight as to prevent removal of the same at will by application of proper upward pressure through the connection with sucker-rods which are used both for driving 10 down and jarring loose the same. Should there be any foreign material, such as sand, between the contacting surfaces of the collar 2 and sleeve 8, or any irregularities in the faces of these parts, such as scorings, or 15 the like, the metal of the ring when spreading will flow into and over such imperfections to shut off all possibility of leakage, thus forming a positive non-leak seat. Similarly the tapered face of the main 20 valve seat 10 is provided with a metal ring such as the ductile metal ring 13 (see Fig. 2) lodged in the annular groove 14 formed in the tapered face of the valve seat 10. The purpose and action of this metal ring 25 is the same as that of the metal ring 11. In practice the distance between the metal rings 11 and 13 will be such that they will simultaneously engage the proper surfaces respectively, the metal ring 11 engaging 30 the inner surface of the diminished bore 3, and the metal ring 13 the inner tapered face 6 of the shoe 5.

It is to be noted by reference to the drawings that the seats 3 and 6 for the ductile 35 metal rings 11 and 13 and likewise the seats for the ductile metal seats 11' and 13' are very slightly tapered so that when the projecting rings shown in Figs. 1 and 12 are forced into said seats by the members 40 8 and 9 which carry said rings the impingement between the rings 11 and 13 is very forcible so as to squeeze and spread the metal into close frictional contact with said seats, thus to form a strong locking effect 45 to anchor the liner in the tubing, said anchorage, however, being capable of being overcome by sufficient force much greater than is likely to come upon a liner except through the purpose of the operator who 50 wishes to withdraw the liner from the tubing.

Inside of the main valve seat 9 is located an inner valve seat 15 having a lower tapered end 16 to fit into an inner tapered 55 face 17 of the main valve seat 9. A ball seat 18 is located in the upper end of the valve seat 15 to receive a ball 19, and a ball cage 20 is positioned above the ball seat and ball, and secured to the valve seat 15. The face of the tapered end 16 is provided 60 with a metal ring 21 lodged in an annular groove 22 similarly to that of the main valve seat 9. When the device is put in place ready for pumping to form the stand valve of the pump, the inner valve seat 15

will be anchored inside of the main valve seat 9 by means of this metal ring 21 in the same manner as metal ring 13 anchors the main valve seat 9.

The inner valve seat may be thrust into the main valve seat in any suitable manner. In the present instance a sucker-rod may be operated to do this. In Fig. 3 a suitable arrangement of sucker-rod is shown. The sleeve 8 is provided with an inner opening 70 23 through which the lowermost sucker-rod 24 is adapted to reciprocate. To the lower end of the sucker-rod 24 is secured a ball cage 25 fastened to the usual piston sleeve 75 26 and provided with a ball 27 and ball seat 28 held in place between the sleeve 26 and ball cage 25. The upper end of the cage 25 presents a shoulder 29 which is of greater diameter than the opening 23 of the sleeve 8.

The pump stock and lower section of tubing 4 is permanently positioned in the well. To introduce the removable working barrel 7, the ball cage 20, and the ball cage 25 fastened to the lower end of the rod 24 are placed inside the working barrel, and then the sleeve 8 secured in place to retain the ball cages 20 and 25 in said working barrel. The working barrel is then lowered by means of a string of sucker rods, and when the metal ring 13 engages the tapered face 6 of the shoe, and the metal ring 11 engages the diminished bore 3 of the collar 2 then the piston sleeve 26 is let down on top of the cage 20 and the sucker-rods pounded down so that the metal rings will spread and form 90 a non-leak seat and anchor as already explained. With this pounding of the sucker-rods, the metal ring 21 of the inner valve seat will be wedged against the inner tapered face 17 of the main valve seat 9, and thereby securely anchor the inner valve seat 15 in place. The liner pump is then ready 95 for the string of sucker-rods to be reciprocated. When it is desired to remove the working barrel it is only necessary to exercise an upward pull on the sucker-rods to break the frictional engagement of the metal rings 11 and 13 in which case the shoulder 29 of the ball cage 25 will engage the lower 100 end of the sleeve 8. The frictional engagement of the metal rings 11 and 13 with the diminished bore 3 and shoe 5 respectively is just sufficient to properly anchor the working barrel for working conditions but not so tight as to make removal of the same difficult.

Fig. 4 illustrates the invention as shown in connection with another form of liner pump. The lower end of the main pump stock 1 is provided with an external screw thread to receive the upper end of a cylindrical collar 2' which has a lower end internally screw-threaded to receive the upper 115 end of a section of tubing 4' which is of smaller bore than the pump stock 1. The 120

lower end of the tubing section 4' is externally screw-threaded to receive the upper end of the shoe 5 which has an inner tapered face 6 at its lower end. When the pump is in operation, the working barrel 7' anchored between the collar 2' and shoe 6 is internally screw-threaded at its upper end to receive the sleeve 8', which has a diameter just sufficient to pass through the bore of the tubing section 4'. The lower end of the barrel 7' is internally screw-threaded to receive the valve seat 9' which has a lower tapered portion 10' to fit into the inner tapered face 6 of the shoe 5. In this removable working barrel 15 the valve stand is integral with said working barrel, the valve seat 9' having a ball seat 30 positioned at its upper end to receive a ball 31 and a ball cage 32 secured to the upper end of a valve seat to hold the ball 20 and ball seat in place. For the purpose of anchoring this form of working barrel in operative position, the sleeve 8' in the present instance is provided with three soft metal rings 11' lodged in annular grooves 25 12', said rings projecting out from the face of the sleeve 8' sufficiently so that they will engage the diminished bore of the lower section of tubing 4' and be there wedged in and spread out when the working barrel 7' is 30 thrust into the tubing section 4'. The lower tapered portion 10' of the valve seat 9' is provided with a ring 13' lodged in the annular groove 14' similar to the metal ring and groove of the modification shown in 35 Fig. 3. In practice, the distance between the metal rings 11' and 13' will be such that they will simultaneously engage the proper surfaces respectively, the metal rings 11' engaging the upper end of the diminished bore 40 of the tubing section 4' and the rings 13' engaging the inner tapered faces of the shoe 5. The remaining parts of these modifications are identical with corresponding parts of the modification shown in Fig. 3 and 45 therefore such description will not be repeated.

Fig. 5 illustrates the invention shown in connection with a form of stationary liner pump. The lower end of the main pump stock 1 is there provided with a shoe 5 having the inner tapered face 6. A stand valve having a valve seat 33 is provided with the lower tapered portion 39 which is adapted to fit into the inner tapered face of the shoe 5. On the upper end of the valve seat 33 is positioned a ball seat 34 to receive a ball 35, said ball seat and ball being retained in place on top of the valve seat by means of a ball cage 36 secured to the valve seat 33. To anchor the stand valve in the shoe 5 the tapered portion 39 is provided with a metal ring 37 lodged in an annular groove 38 formed in the face of said tapered portion 39. This ring projects a sufficient distance 65 from the face of said tapered portion 39, so

that when said stand valve is thrust into the shoe 5 the metal ring 37 will be wedged and spread out similarly to the metal rings of the other constructions.

Standard ball cages may be used for the stand valves in the constructions shown. The upper ends of the ball cages have either a male screw thread or a female screw thread. A screw thread on the upper end of the ball cage is not required for the present invention, it being shown merely to indicate that standard ball cages may be used, the stand valves in Figs. 3 and 4 having a female screw thread and the stand valve in Fig. 5 having a male screw thread. Should it be required at any time to remove the stand valve of the construction shown in Fig. 5 from the shoe in which it is anchored, the screw-threaded upper end might then be used to good advantage, as it would then only be necessary to insert a correspondingly screw-threaded rod into the tubing, fasten the same to the ball cage, and then withdraw it, thereby withdrawing the stand valve. Obviously, the lower end of the lowermost sucker rod may be provided with such a corresponding screw thread in order that the sucker rod may be manipulated to remove such stand valve.

Obviously, this non-leak seat and anchor 95 may be used in various devices, and that variations in the details of construction may be made without departing from the general scope of the invention.

It is to be noted that when the liner barrel 100 7 is lowered down through the tubing of the metal ring 11 or 11' and engages the smaller bore of the collar or top of the working barrel, it eliminates all possibility of an accumulation of sand behind the barrel walls 105 that would freeze and make removal difficult, as the sand cannot settle down out of the pump tubing 1 into the space between said liner barrel 7 and the tubing section 4.

We claim:-

1. In combination, a shoe having an inner tapered face at its lower end, a collar having an intermediate diminished bore, a tubing section connecting said collar to the upper end of the shoe, a working barrel inside the tubing section and provided at its lower end with a tapered seat to fit the shoe, said seat having an annular groove, a packing ring in the groove to seat on the tapered face of the shoe, a sleeve connected to the upper end of the working barrel and provided with a second annular groove, and a packing ring in said second annular groove to engage the diminished bore of the collar.

2. The combination with a removable liner pump having an outer tubing provided with a shoe at its lower end, said shoe having its inner face tapered, said tubing having a collar at a predetermined distance from said shoe, said collar having a dimin-

ished inner bore, and a removable working barrel having a lower tapered portion and an upper sleeve, the distance between said lower tapered portion and sleeve corresponding to the distance between the shoe of said tubing and its collar, of a soft metal ring provided on the face of the lower tapered portion and a soft metal ring provided on the face of the upper sleeve, said metal rings being sufficiently soft so that when the lower tapered portion of the working barrel engages the shoe of the tubing and the upper sleeve of the working barrel engages the collar of the tubing, said metal rings will spread and offer sufficient friction so that the working barrel will be anchored into said tubing.

3. The combination with a removable liner pump having an outer tubing provided with a shoe at its lower end, said shoe having its inner face tapered, said tubing having a collar at a predetermined distance from said shoe, said collar having a diminished inner bore, and a removable working barrel having a lower tapered portion and an upper sleeve, the distance between said lower tapered portion and the sleeve corresponding to the distance between the shoe of said tubing and its collar, of a soft metal ring provided on the face of the tapered lower portion and a soft metal ring provided on the face of the upper sleeve, said metal rings being sufficiently soft so that when the lower tapered portion of the working barrel engages the shoe of the tubing and the upper sleeve of the working barrel engages the collar of the tubing, said metal rings will spread and offer sufficient friction so that the working barrel will be anchored in said tubing; and an inner tapered face in the lower tapered portion of the working barrel, a stand valve having a lower tapered portion to seat into said inner tapered face of the working barrel, a soft metal ring provided in the face of said lower tapered portion of the stand valve, said soft metal ring being adapted to spread when the stand valve is forced into the lower tapered portion of the working barrel to form a non-leak seat and offer sufficient friction so that the stand valve will be anchored in said working barrel.

4. In a liner pump, the combination with a section of tubing of smaller bore at the lower end of the main tubing, a shoe secured to the lower end of said section of tubing, said shoe having an inner tapered face, and a removable working barrel having a lower tapered portion and an upper sleeve, the distance between said tapered portion and sleeve corresponding to the distance between the shoe of said tubing and the upper edge of the lower section of tubing, of a soft metal ring provided on the face of said lower tapered portion and a soft metal ring

provided on the face of the upper sleeve, said metal rings being sufficiently soft so that when the lower tapered portion of the working barrel engages the shoe of the tubing and the upper sleeve of the working barrel engages the upper portion of the lower section of tubing said metal rings will spread to form a non-leak seat and offer sufficient friction so that the working barrel will be anchored in said tubing.

5. A device of the character described comprising a male member and a female member, said female member having a slightly tapered seat, a plurality of annular ductile metal rings secured in the face of said male member, said male member being slightly tapered to fit said seat, said rings being adapted to spread to frictionally engage said seat when said male member is thrust into the corresponding tapered female member, the metal rings when spread engaging the female member with sufficient friction so as to anchor the male member in said female member.

6. The combination with a removable liner pump having a lower section of tubing of smaller bore than the main pump stock and a shoe connected to the lower end of said lower section of tubing, said shoe having an inner tapered face, a removable barrel having a lower tapered end, means for anchoring said barrel in said lower section of tubing, said means comprising a plurality of soft metal rings provided around the upper end of said removable barrel to engage the upper end of said lower section of tubing and a soft metal ring around the lower tapered end of said barrel to engage the inner tapered face of said shoe, said metal rings being sufficiently soft so that when said barrel is thrust into said lower section of tubing the metal rings will spread and offer sufficient friction so that the working barrel will be anchored in said tubing.

7. A combination seat and anchor for liner pumps comprising a female member, a male member having an annular groove in its outer face, and a ring of ductile metal provided in said groove, said ring being adapted to spread into frictional contact with said female member when said male member is forced into said female member, thus to form a non-leak seat.

8. A device of the character described comprising a female member, a male member having an annular groove in its outer face, and a ring of ductile metal anchored in said groove, said ring being adapted to project slightly beyond the face of the male member so that when said male member is forced into said female member, the metal ring will be thereby forcibly spread and made to frictionally engage the female member and form a non-leak anchor seat.

9. A device of the character described

- comprising an annular ductile metal ring secured in the face of a male member, said male member being tapered, said ring being adapted to be spread through contact with 5 the female member when said male member is forced into a correspondingly tapered female member, the metal ring when thus forcibly spread engaging the female member with sufficient friction so as to anchor the 10 male member in said female member.
10. The combination with the shoe of a liner pump, the inner face of said shoe being slightly tapered, and a stand valve having its lower outer face slightly tapered and 15 adapted to seat into the inner slightly ta-
- pered portion of said shoe, of a ductile metal ring secured on the tapered portion of said stand valve, said metal ring being adapted to be forcibly spread when said stand valve is forced into said shoe so as to 20 form a non-leak anchor seat.
- In testimony whereof, we have hereunto set our hands at Bakersfield, California, this 5th day of December, 1913.
